TREATMENT OF FABRICS

Maurice M. Kasanof, Bronx, N. Y.; David R. Kasanof and Abraham Kriegel executors of said Maurice M. Kasanof, deceased

Application November 7, 1932, Serial No. 641,521

4 Claims. (Cl. 26—55)

My present invention relates generally to the treatment of fabrics for purposes such as drying, shrinking, bleaching and similar operations.

I have illustrated my invention as employing an apparatus particularly adapted and intended for the fluid treatment of fabrics in tubular form.

Among the general objects of my invention are the provision of an arrangement whereby the treatment of the fabric may be varied in accordance with the requirements of the particular fabric being treated, and of an arrangement whereby the treatment may be controlled to vary the effects to be produced on any given fabric.

Other objects are: the provision of an arrangement whereby a fabric moving across a stream of treating fluid may have a substantial portion of it exposed to the fluid at any given moment; the provision of an arrangement whereby all portions of the fabric are subjected to the treatment for a substantial time interval; the provision of an arrangement whereby the resistance offered to the movement of the fabric during treatment is minimized; the provision of an arrangement whereby the area of fabric exposed at one time may be varied so that a change in the time of treatment may be effected; the provision of an arrangement whereby the shrinking or stretching and other changes of form of the fabric during treatment may be controlled; the provision of an arrangement whereby a selected treating fluid or a combination of treating fluids may be used; the provision of an arrangement whereby the treating fluid is discharged freely and with little resistance, and effectively distributed with relation to the fabric; the provision of an arrangement whereby the treating fluid is prevented from escaping through passages other than those intended for its discharge; and the provision of an arrangement whereby condensed moisture or other matter may be conveniently separated from the treating fluid before its application to the fabric.

In the specific embodiment herein disclosed, I show the employment of two members to form the end walls of the treating chamber, the side end closure for the chamber being formed by the fabric itself as it is moved during the treating process, and I attain some of the objects of my invention by spacing these two members a substantial distance apart so as to expose to the action of the treating fluid a substantial fabric length, so that the fabric portions are subject to treatment by the treating fluids during a very substantial portion of the movement of the fabric, and therefore for a very substantial time.

I attain still further objects of the invention

by making these two members relatively adjustable so as to vary the length of the treating chamber, and therefore of the fabric length exposed to treatment. As a consequence the time during which any one portion of the fabric is exposed may be varied to suit a given kind of fabric or to produce a desired effect, and it is also obvious that by increasing the area exposed at one time, the speed of travel of the fabric may be increased without changing the character of the treatment, and thereby the total time of treatment may be shortened.

These two end members serve the additional function of guiding the fabric during its travel, and I attain still further objects of my invention by so contouring them as to subject the fabric to a minimized resistance to its travel thereover and for treatment purposes, and also to a minimum of injury to the fabric. By using members of various sizes and contours, the shrinking or stretching of the fabric may be controlled.

I attain other objects of the invention by discharging the treating fluid into the treating chamber instead of directly from apertures through the fabric thereby causing it to spread before it passes through the fabric so that the resistance to discharge is lessened and a greater area of fabric penetrated by the fluid than if the discharge were directly from the nozzles through the fabric.

I further provide, for the attainment of other objects, a specially constructed end member for the treating chamber whereby leakage, waste of treating fluid, and ineffective treatment of the fabric is prevented.

By the provision of a peculiar discharging arrangement, I am able to control the moisture content of the treating fluid, it being understood that in using the term "moisture" I mean not merely condensed water vapor, but also condensed matter of other kinds.

When it is desired to dry a fabric, air, either hot or cold, will ordinarily be used, and when it is desired to stretch or shrink the fabric, steam may be used. My invention also provides for the use of a mixture of steam and air.

It will be understood, however, that the term fluid is not to be considered as restricted to these particular fluids unless specifically called for by the language of the claims.

It will be obvious that changes in the details hereinafter described and illustrated for the purpose of explaining the nature of my invention may be made by those skilled in the art without departing from the spirit and scope of my in-

vention as expressed in the appended claims. It is therefore intended that these details be interpreted as illustrative merely and not in a limiting sense. It is further to be understood that while I have described and illustrated embodiments which attain all of the enumerated objects, embodiments may be employed that utilize only some or even only one of the objectives, and not all of them.

10 For the attainment of these objects and such other objects as may hereinafter appear or be pointed out, I have illustrated one embodiment of my invention in the drawings, wherein:

15 Figure 1 is a front elevation showing one illustrative embodiment of my invention;

Figure 2 is a section, on a greatly enlarged scale, on line 2—2 of Figure 1, looking in the direction of the arrows;

20 Figure 3 is an elevational view of another embodiment of my invention;

Figure 4 is an exploded view of certain details of my invention;

25 Figure 5 shows a modified form of the discharge openings by which the fluid is emitted into the treating chamber;

Figure 6 is a sectional view on line 6—6 of Figure 5, looking in the direction of the arrows; and

30 Figure 7 is an elevational view of a modified form of end member, portions being broken away to more clearly disclose the construction.

Referring to Figures 1 and 2, it will be observed that the chamber here shown for treating a tubular fabric 70, is constituted by the 35 spaced members 20 and 21 which form the ends of such chamber, and by the fabric 70 itself, which forms the outer walls of the chamber.

For purposes of treatment the fabric is caused to move over the members 20 and 21 and during such motion, a treating fluid is admitted into the chamber and discharged through the walls of the fabric. The effectiveness of the treatment obviously depends on the length of time during which a given portion of the fabric is exposed to 45 the action of the fluid, and such time of exposure will depend on the speed at which the fabric moves in relation to the fluid and on the area of fabric exposed at one time. This area depends on the size of the treatment chamber. 50 For example, by spacing the members 20 and 21 eight feet apart and moving the fabric at the rate of four feet per second, any given portion of the fabric will be exposed for two seconds, while if the spacing is only four feet, the exposure will be 55 only one second.

For these reasons I provide an arrangement whereby the members 20 and 21 may be widely separated and thereby provide a relatively elongated treating chamber. And further, I make 60 the spacing adjustable, so that the area of fabric exposed to treatment may be varied within wide limits and the treatment thereby adapted to obtain various effects on various fabrics, without resorting to the expedient of varying the speed of the fabric. It is of course obvious that this speed also may be varied if desired and still further flexibility of control attained thereby.

70 The adjustability of the spacing of members 20 and 21 is attained by making at least one of them adjustable in relation to the other one, and in the disclosure I have shown both of them adjustable.

75 The members 20 and 21 are shown as provided with annular flanges 25 for the twofold purpose of securing a minimum area of contact between

said flanges and the fabric as it is led there-over, so as to reduce friction, and of providing a smooth and rounded surface which will not cause injury to the fabric. The guide members are further shown as mounted on split collars 32 and 33, each adjustable on the conduit 11, which is shown as passing centrally through the treating chamber, and as being provided with apertures 14, through which the treating fluid may be discharged into the chamber.

10 The conduit 11 is shown closed at its top, as by cap 16 and as connected, in any suitable manner, such as by the fitting 12, closed by cap 12a, to a supply pipe 13, by which the treating fluid is led from its source to the conduit 11 and discharged through apertures 14. A platform 60 may be provided through which the conduit passes and below which are located the supply pipe 13 and its auxiliary parts. This platform serves as a suitable gathering place for the fabric before 15 treatment and protects it against soiling and other injury, due to contact with parts other than the conduit.

20 In Figure 2 the fabric, after its passage over guide members 20 and 21, is shown as led over a spreader or stretching frame 50, which may be used for stretching the fabric and also for spreading it so that it will be adapted to pass into a suitable pulling device (not shown), such as a pair of drawing rollers, which will furnish the 25 actuating force by which the fabric 70 is drawn over the guide members 20 and 21. The stretching frame is shown as provided with angularly disposed portions 51, whereby the fabric is guided on to the wider portions of the spreader, and with 30 inwardly turned lugs 52 pivotally disposed in ears 24 located on the upper guide member 21. This results in a construction whereby the spreader may be readily removed for which purpose it is made of slightly yielding or resilient material 35 and it will also be observed that the pivotal mounting permits tilting of the spreader where this is desirable.

35 The details of the construction of guide members 20 and 21 and the adjustable collars 32 and 33 will be understood by referring to Figure 4 in connection with Figure 2. It will be seen that the guide member 20 there shown is provided with key-hole slots 26 and has a central opening 28 so that it may be passed over the conduit 11 and seated in place on the adjustable collar 32. The opening 28 is made large enough so that it will 40 pass over the cap 16, which will insure ready removal of the member 20 and its replacement by 45 similar other members of various sizes and shapes.

50 The collar 32, as illustrated, is composed of two complementary portions 34 and 35 which are adjustably held together by screws 42 passing freely through holes 40 in ears 39 on part 35 and into threaded openings 37 on ears 36 of part 34, this arrangement permitting adjustability of the collar with relation to the conduit. Screws 44, corresponding in number and location to the key-holes 26 in guide member 20, are positioned in the collar 32, so that the member 20 may be 55 removably mounted on collar 32 by passing the enlarged portions of its key-holes over the heads of screws 44 and then giving it a twist so that the narrow portions of the key-holes pass under the screw heads. It will be understood that member 20 and collar 32 are identical in construction with the upper guide member 21 and collar 33, except that the member 21 carries the ears 24 60 aforementioned for accommodating the stretcher frame.

By this arrangement it will be seen that the guide members are removably mounted in place so that they may be readily replaced by other guide members of different sizes or different shapes or both, so that they may serve to guide the tubular fabric in its course through the apparatus and cause it to shrink when said guide members are small in dimensions in relation to the tubular fabric or to stretch when their dimensions are greater than the dimensions of the fabric. Instead of being circular, the guide members may be given other shapes, so as to affect the forming of the fabric, and said guide members are furthermore adjustable on said conduit by the screws 42 provided on the adjustable collars.

By making the conduit 11 of suitable dimensions, great variation in the length of the treating chamber, which is formed by the space between the guiding members 20 and 21, may be achieved, so that by spacing them a great distance apart, a large area of the tubular fabric may be exposed for treatment at one time, and the time of treatment for a given length of fabric correspondingly shortened. To further increase the effectiveness of an enlarged chamber, I may use a greater number of apertures 14 than are illustrated and these may be distributed along the conduit.

The operation of this embodiment of my invention will now be described. The guide members 20 and 21 together with spreader 50 are first of all removed, either by opening split collars 32 and 33, or by removing 20 and 21 from their seats on the collars, and the tubular fabric is placed over the conduit 11 and gathered in collapsed form over the platform 60. This is indicated at the bottom of Figure 2. Parts 20, 21 and 50 may now be replaced, 20 and 21 being placed on opposite sides of the apertures, and spaced from each other so as to give a treating chamber of the desired length. The end of the fabric is next drawn over these parts and inserted into the pulling device. The treating fluid is then admitted into the treating chamber and the pulling apparatus brought into action to draw the fabric through the apparatus and thereby expose its entire length to the treatment.

In Figure 3 is shown a modified form of my invention in which all parts corresponding to those of the form of Figure 1, have been numbered similarly, except that each numeral has been primed. This form differs from the preceding one in having, in addition to the features of the other form, a pipe 90 entering the conduit at one side thereof, but preferably below the platform 60', so as not to come into contact with the fabric and interfere with the treating operation, by means of which a second treating fluid may be introduced into the conduit 11' either alternatively to or simultaneously with the fluid coming through 13'. Figure 3 also shows a valve 91 to control the fluid in pipe 90 and a valve 92 to control the fluid in pipe 13. By the use of these valves, mixtures of the two fluids in any desired proportion, may be effected.

In Figures 5 and 6 is shown a modification of the discharge openings 14 of Figures 1 and 2. The modified discharge openings are here indicated by the numeral 14''. In this modification each opening 14'' is the outlet of a short tube 80 mounted in the walls of the conduit 11''. When a fluid such as steam is discharged, the temperature of which is higher than that of the walls of the conduit or of the air surrounding

the conduit 11'', there will be a tendency for the steam to cool and to condense on the walls of the conduit, whereas, the steam in the interior portions of the conduit will maintain its temperature. By using the pipes 80, the steam coming out of the orifices 14'' will be the hotter and drier steam from the interior portions of the conduit, while the condensed steam will collect on the walls of the conduit from which it may be removed by any suitable drainage provision, as will be obvious to those skilled in the art, it being believed unnecessary to describe such arrangement in detail. It will thus be evident that I provide a separating or filtering action by which the moisture content of a treating fluid may be controlled at the point of delivery.

In Figure 7 I have attempted to illustrate a modified form of the member 20.

When it is desired to shrink a tubular fabric, say one having a diameter of 26", to a diameter 20 of 20", it will be evident that the member 20 must not exceed 20" in diameter. On the other hand if member 20 is made 20" in diameter and the fabric passing over it is 26" in diameter, it will be obvious that the treating fluid can escape through the space between the two instead of passing through the fabric.

To avoid this, I may use, in place of the member 20, a member 120 provided with an upstanding annular portion having a channel 122 and beaded surfaces 123 on either side thereof. A resilient member 124, shown by way of illustration as a coiled spring under suitable tension is disposed in the channel 122 and serves to keep the fabric 10, as it passes between spring 124 and the member 120, in contact with the surface of said member, with a pressure sufficient to prevent leakage. The member 120 may be mounted removably on a split collar 132, corresponding to collar 32, this construction being similar to that shown for 20 and 32.

It is to be understood that the surface of channel 122 and of beads 123 will be made smooth and of as small area as possible so as to reduce friction to as small a value as possible, and that the surface of the spring 124 will also be restricted and made smooth for the same purpose.

While I have described this modified form of end member as alternative to member 20, it will be understood that it may also be used, with suitable modifications, in place of member 21, and that either end or both ends of the treating chamber may be provided with this modified form of end member.

Having thus described my invention and illustrated its use, what I claim as new and desire to secure by Letters Patent is:

1. For use with apparatus for treating tubular fabrics, having a treating chamber, the outer walls of which are constituted by the tubular fabric to be treated, and having a conduit for supplying treating fluid to the chamber, a split collar adjustably mounted on the conduit and carrying removably mounted thereon means for guiding the tubular fabric, said means constituting one of the ends of said chamber.

2. For use with apparatus for treating tubular fabrics, having a treating chamber, the outer walls of which are constituted by the tubular fabric to be treated, and having a conduit for supplying treating fluid to the chamber, a collar comprising two complementary sections separably and adjustably related and adjustably mounted on the conduit and carrying, removably mounted there-

on, means for guiding the tubular fabric, said means constituting one of the ends of said chamber.

3. In treating apparatus for tubular fabrics, a conduit for conducting a treating fluid, said conduit being provided with at least one aperture for the discharge of said fluid, the entrance portions of said apertures being in the form of tubular members projecting horizontally from the inner walls of said conduit, whereby they are positioned so as to oppose the entrance and flow therethrough

of particles of fluid moving downward under the action of gravity.

4. A device for treating tubular fabrics comprising, in combination, a conduit, a pair of members secured to the conduit over the peripheral edges of which the tubular fabric is drawn, at least one of the members being adjustably secured so as to vary the distance between the members, and a spreader attached to one of the members, over which the fabric is likewise drawn. 5

MAURICE M. KASANOF. 10
